MOTOR OPERATED SPRAY DEVICE

Forrest M. Duncan, Long Island City, N. Y., assignor, by mesne assignments, to Champion Implements Corporation, New York, N. Y., a corporation of New York

Application August 17, 1949, Serial No. 110,778

10 Claims. (Cl. 299—97)

1

The present invention is directed to equipment for spraying various liquids such as paints and lacquers, and commonly known as a spray gun.

Devices of this character have been known for some time and usually have consisted of a compressor unit with a tank for compressed air, with a spray apparatus including a nozzle whereby the compressed air forces the liquid through the nozzle to form a spray. Such apparatus is quite bulky and can be used only where a large amount of work is to be done or where continuous application of the device takes place. While it may be portable, it requires several men for transportation, and usually in conjunction with a vehicle.

It has also been proposed to provide equipment which is readily portable and which may be readily handled by the operator. For instance, in one type there was provided a magnetic motor with a pivoted armature operating a pump unit. Said unit was inserted into a container of the liquid and when the motor was operated, the liquid was sprayed. However, this type of equipment had a number of disadvantages in that it was unbalanced and was difficult for the operator to hold with one hand. The pump arrangement being in the liquid soon became caked by the solid material in the liquid and ceased to function. It was most difficult to disassemble the device for the purpose of cleaning and the device was relatively complicated and expensive in construction.

The present invention is intended and adapted to overcome the difficulties and disadvantages inherent in prior devices of the type described, it being among the objects of the present invention to provide a spray gun which is simple in construction, which may be transported readily and which is highly effective in operation.

It is also among the objects of the present invention to provide a structure of spray gun which may be readily disassembled for cleaning or replacement purposes without the necessity of special tools or special skill on the part of the operator.

It is further among the objects of the present invention to provide a spray gun of the type described wherein maximum effectiveness of the power in the electromagnetic motor is obtained so that a steady stream of liquid may be obtained.

In practicing the present invention, there is provided a hollow body which is usually rectangular in cross-section and in which an electromagnet is held. The poles of the magnet extend rearwardly adjacent to a vertically placed

2

armature which is preferably not pivoted but rests upon a ledge in the bottom of the hollow member so that it is entirely free to move and thus to develop the maximum power of the motor.

Extending rearwardly from the bottom of the hollow body is a hollow handle in which is placed a suitable switch for operation of the motor. Electrical connections from a source of current enter the lower end of the handle and pass into the hollow body being connected to the motor. A trigger operating device for the switch is pivoted at the lower front end of the body so that the pressure of a finger may close the switch to operate the motor, there being provided a spring for retracting the trigger when pressure is released.

Extending forwardly from the top of the hollow body is a barrel containing the operating elements. Within the barrel is fixed a cylindrical elongated bearing through which a push rod for a piston is intended to operate horizontally. The upper end of the armature contacts the rear end of the push rod for the piston during the operation thereof. A suitable spring connected to the piston retracts it rearwardly. In the front of a barrel is a sleeve having a central opening and a valve seat on which a spring pressed ball is adapted to seat. A transverse opening in the sleeve behind the seat allows liquid to be drawn into the same to be ejected past the seat. A nozzle embraces the forward end of the sleeve and is threaded into the front end of the barrel.

In the accompanying drawing constituting a part hereof, and in which like reference characters indicate like parts,

Fig. 1 is a side elevational view of a spray gun made in accordance with the present invention, some parts being cut away for clearness;

Fig. 2 is a fragmentary front elevational view of a spray gun shown in Fig. 1;

Fig. 3 is a vertical cross-sectional view thereof taken along the line 3—3 of Fig. 2 and

Fig. 4 is a fragmentary, vertical cross-sectional view of a modified form of a spray gun.

Hollow body 1 which is roughly rectangular in cross-section is provided with a cover 2 held by screws 3. An electromagnet 4 within body 1 has poles 5 extending rearwardly, as shown in Figs. 1 and 3. A ledge 6 in the bottom of body 1 provides means for a vertically placed armature 7 to rest when the device is not in operation. An overhanging portion 8 at the top of body 1 just above armature 7 provides a stop for limiting the motion of the upper end 9 of the armature. 55 An adjustable set screw 10 allows adjustment of

the length of horizontal movement of armature 1. Bumper 10' in the inner end of screw 10 is adapted to absorb the shock of the impact of armature 9 in its movements.

At the lower end of body 1 and integral therewith is a rearwardly extending handle 11 within which the switch 12 is held. A cover 2' which may be integral with cover 2 is held in position on the handle by screws 3'. Blade 13 of switch 12 has a pin 14 extending outwardly from the top of handle 11. Wires 15 extending from a source of current pass into the lower end of the handle through an opening (not shown) and are connected to switch 12 and magnet 4. A trigger 16 is pivoted at 17 to the lower front end of body 1 and is provided at the lower end with a finger grip 18.

Extending forwardly from the top of body 1 is a barrel 19 having a fin 20 integral therewith, the latter being formed with hook 21 providing means for hanging the device from a suitable support. The position of hook 21 is such that when the assembly is made, it is hung at approximately the center of gravity thereof either when not in operation or even when in use.

The barrel has a horizontal bore 22 at the rear portion thereof with a shoulder 23 at an intermediate portion so that bore 24 in the front of the barrel is of larger diameter than bore 22. An elongated cylindrical bearing member 25 or push rod guide is fixed into bore 22. A push rod 26 contacts a piston 26 and fits snugly in the bearing for reciprocation therein. A coil spring 27 surrounds the rear of piston 26 and retracts the same after actuation by armature 1.

A sleeve 28 in bore 24 contacts soft metal washer 29 at shoulder 23. It has a central bore or cylinder 30 with a transverse opening 31 communicating with an external groove 32 on the face thereof. Front end of piston 26 is slidable in the cylinder past opening 31.

The front of bore 30 is enlarged as shown at 33, the junction forming a shoulder 34 constituting a valve seat. Ball 35 biased rearwardly by coil spring 36 fits on seat 34. Nozzle 37 having a jet 38 in a central portion thereof and a hollow body portion is adapted to embrace the front end 39 of sleeve 28 and forms a stop for the end of spring 36. Nozzle 37 is externally threaded and fits into cooperating threads at the forward end of barrel 19. A soft metal washer provides a seal at the junction of nozzle 37 and sleeve 28.

A downwardly extending tube 40 is fitted into screw 41 which is threaded at 42 into the underside of barrel 19. Space 43 above tube 40 communicates with groove 32. Cap 44 which is internally threaded is united with barrel 19 and pipe 40 held in position as shown in Fig. 3 by screw 41. A container 45 such as a can or jar having the neck externally threaded and carrying the liquid to be sprayed is threaded into cap 44.

In the operation of the device the liquid is placed in container 45 which is screwed into cap 44. Wires 15 are connected to a source of current and the operator grasps handle 12 with his finger on grip 18. Upon pressing the grip, the circuit is closed through switch 12, causing rapid shifting of armature 7 from left to right. There is hampering of the movement because the armature in effect floats in the space it occupies. At each stroke to the right, it impinges on 26'-26, moving it forward and causing liquid in the bore 30 to be ejected past ball 35 and out of nozzle 38. Then armature 7 is retracted by the force of spring 27 and ball 35 is seated by spring 36.

This movement creates a slight vacuum which raises liquid in tube 40 into bore 30. The succeeding operations at a high speed, dependent upon the number of cycles in the alternating current used, cause practically continuous ejection of liquid through jet 38 so that a continuous stream is obtained.

When it is desired to clean or repair the device, it is merely necessary to unscrew nozzle 37, whereby the ball 35 and spring 36 may be removed by shaking sleeve 28 which is also readily removable. Piston 26 and spring 27 may be removed by turning the front of barrel 19 downwardly and gently shaking the gun, whereby the piston 26 and its attached spring 27 will fall out. For cleaning tube 40 and associated parts, it is merely necessary to remove screw 41. A drain 46 allows liquid from bore 22 to flow back into container 45.

In Fig. 4, there is shown a modification in which tube 40 is fixed into opening 31 of sleeve 28. To permit ready removal of the sleeve and attached tube from the spray gun, a vertical slot 47 is formed in the lower portion of the front end of barrel 19. After the removal of cap 44 and nozzle 37, sleeve 28 and tube 40 may be slipped out of the end of the gun.

Although the invention has been described setting forth a single specific embodiment thereof, various changes in the details of construction may be made within the principles herein set forth. The invention is, therefore, to be broadly construed and not to be limited except by the claims appended hereto.

I claim:

1. A spray gun comprising a hollow body, an electromagnet therein, an armature adjacent the rear of said magnet and extending upwardly, a handle extending from the lower portion of said body, a switch in said handle, a trigger for manually operating said switch, electrical connections between said switch, magnet and a source of electricity, a barrel extending horizontally from the top of said body in alignment with the upper end of said armature and above the top of said magnet, a piston therein, said armature adapted to contact said piston, means secured to the lower side of the front portion of said barrel for holding a depending container, and means associated with said piston for spraying fluid at the outer end of said barrel.

2. A spray gun comprising a hollow body, an electromagnet therein, an armature adjacent the rear of said magnet and extending upwardly, a handle extending from the lower portion of said body, a switch in said handle, a trigger for manually operating said switch pivoted at the lower portion of said body, electrical connections between said switch, magnet and a source of electricity, a barrel extending horizontally from the top of said body in alignment with the upper end of said armature and above the top of said magnet, a piston, means secured to the lower side of the front portion of said barrel for holding a depending container therein, said armature adapted to contact said piston, and means associated with said piston for spraying fluid at the outer end of said barrel.

3. A spray gun comprising a hollow body, an electromagnet therein, an armature adjacent the rear of said magnet and extending upwardly, a ledge in said body on which said armature lies, a handle extending from the lower portion of said body, a switch in said handle, a trigger for manually operating said switch, electrical con-

nections between said switch, magnet and a source of electricity, a barrel extending horizontally from the top of said body in alinement with the upper end of said armature and above the top of said magnet, a piston, means secured to the lower side of the front portion of said barrel for holding a depending container therein, said armature adapted to contact said piston, and means associated with said piston for spraying fluid at the outer end of said barrel.

4. A spray gun comprising a hollow body, an electromagnet therein, the poles of said magnet extending horizontally, an armature adjacent the rear of said magnet and extending upwardly, a handle extending from the lower portion of said body, a switch in said handle, a trigger for manually operating said switch, electrical connections between said switch, magnet and a source of electricity, a barrel extending horizontally from the top of said body in alinement with the upper end of said armature and above the top of said magnet, a piston, means secured to the lower side of the front portion of said barrel for holding a depending container therein, said armature adapted to contact said piston, and means associated with said piston for spraying fluid at the outer end of said barrel.

5. In a spray gun, a barrel, a piston therein, a nozzle at one end and means for actuating said piston at the other end thereof, a removable sleeve having a valve seat therein in said barrel adjacent said nozzle, a ball valve contacting said seat, a spring in said sleeve bearing on said valve, said nozzle having a hollowed portion threaded into said barrel, the outer end of said sleeve fitted in said hollow, washers at both ends of said sleeve, one of said washers contacting a shouldered portion of said barrel and the other washer contacting the inner end of said nozzle, an opening in the face of said sleeve rearwardly of said valve and a tube attached to said barrel in communication with said opening, the free end of said tube adapted to be immersed in fluid to be sprayed.

6. In a spray gun, a barrel, a piston therein, a nozzle at one end and means for actuating said piston at the other end thereof, a removable sleeve having a valve seat therein in said barrel adjacent said nozzle, a ball valve contacting said seat, a spring in said sleeve bearing on said valve, an opening in the face of said sleeve rearwardly of said valve and a circumferential groove in said sleeve at said opening, a tube attached to said barrel in communication with said opening, the free end of said tube adapted to be immersed in fluid to be sprayed.

7. In a spray gun, a barrel, a piston therein, a nozzle at one end and means for actuating said piston at the other end thereof, a removable sleeve having a valve seat therein in said barrel adjacent said nozzle, a ball valve contacting said seat, a spring in said sleeve bearing on said valve, an opening in the face of said sleeve rearwardly of said valve and a tube attached to said barrel in communication with said opening, the free end of said tube adapted to be immersed in fluid to be sprayed, an elongated bearing fixed in the central portion of said barrel, a pushrod fitted therein and extending from both ends, said pushrod having one end in contact with one end of 70 said piston.

8. In a spray gun, a barrel, a piston therein, a nozzle at one end and means for actuating said piston at the other end thereof, a removable sleeve of uniform diameter in which said piston slides, an enlargement at the front of said sleeve, said enlargement having a valve seat therein in said barrel adjacent said nozzle, a ball valve contacting said seat, a spring in said sleeve bearing on said valve, an opening in the face of said sleeve rearwardly of said valve and a tube attached to said barrel in communication with said opening, the free end of said tube adapted to be immersed in fluid to be sprayed, an elongated bearing fixed in the central portion of said barrel and extending rearwardly therefrom, a separate pushrod for a pushrod fitted therein and extending from both ends, said pushrod having one end in contact with one end of said piston, and a spring at the nozzle end of said piston biasing the same rearwardly, a body rearwardly of said barrel into which said bearing extends, a magnet below said bearing in said body, a horizontally movable armature rearwardly of said magnet and extending above the same, said piston being in axial alinement with the top of said armature.

9. A spray gun comprising a hollow body, an electromagnet therein, an armature adjacent the rear of said magnet and extending upwardly, a handle extending from the lower portion of said body, a switch in said handle, a trigger for manually operating said switch, electrical connections between said switch, magnet and a source of electricity, a barrel extending horizontally from the top of said body in alinement with the upper end of said armature and above the top of said magnet, a piston therein, a pushrod in axial alinement with said piston, means secured to the lower side of the front portion of said barrel for holding a depending container, said armature adapted to contact said rod, and means associated with said piston for spraying fluid at the outer end of said barrel.

10. In a spray gun, a barrel, a piston therein, a nozzle at one end and means for actuating said piston at the other end thereof, a removable sleeve having a valve seat therein in said barrel adjacent said nozzle, a ball valve contacting said seat, a spring in said sleeve bearing on said valve, an opening in the face of said sleeve rearwardly of said valve and a tube fixed in said opening, the free end of said tube adapted to be immersed in fluid to be sprayed, said barrel having a slot extending from the front end thereof to said tube, said slot adapted to permit the removal of said sleeve and tube as a unit from said barrel.

FORREST M. DUNCAN.
